PROCESS OF TREATING METALLIC SALT SOLUTIONS

Paul C. Rich, Los Angeles, Calif., assignor to
Vapor Treating Processes, Inc., Los Angeles,
Calif., a corporation of California

Application June 11, 1934, Serial No. 730,146

14 Claims. (Cl. 23—50)

This invention relates to revivification of metallic salt solutions associated with impurities, which have been used in purifying and refining hydrocarbon oil by contact therewith, and is especially adapted for revivifying such salt solutions after use as described in U. S. Patent #1,809,170, issued to Arthur Lachman June 9, 1931, Process of refining hydrocarbon oils, which describes the purification and refining of hydrocarbon oils in vapor phase, using water solutions of metallic salts or mixtures thereof, such as the chloride, bromide, iodide, sulphate, nitrate, etc., of zinc, copper, cadmium, mercury, iron, chromium, manganese, aluminum, nickel and cobalt, which are heavy metal salts.

In general, this invention may be used to revivify for reuse any of the metallic salt solutions which have been used for purifying and refining hydrocarbon oils by any liquid or vapor phase method known in the art, and which may also include, in addition to the above named salts, salt solutions of magnesium, calcium, ammonia, oxychlorides, mixed base oxyhalides and double salts.

Metallic salt solutions when used to refine hydrocarbon oils, such as gasoline, naphtha or other like hydrocarbon oil distillates, by liquid or vapor phase methods, take up impurities, notably oil coloring matter which is in part nitrogen base compounds and other organic oils, or oil compounds of unknown chemical composition, until they are rendered more or less inert by the inhibiting action of the adsorbed oils or constituents, which may be in part in chemical combination therewith. Also, a portion of the metallic salt of the solution may be converted to the corresponding sulphide, this conversion to the sulphide depending upon the reactive sulphur content of the oil stock being treated.

In the use of water solutions of metallic salts, such, for example, as concentrated solutions of zinc chloride, for purifying and stabilizing gasoline stocks or other distillates by contact therewith at elevated temperatures, I have discovered that the compounds which gradually render inert the zinc chloride in use are composed largely of nitrogen base salts, such as pyridine hydrocarbons or other like nitrogen base acid salts, and resinous compounds, particularly when gasoline stocks derived from cracked petroleum oil products are treated. I believe that the resinous compounds are produced during the treatment of gasoline stock with metallic salt solutions at elevated temperatures by polymerization of acetylene, diolefine and like hydrocarbons contained in the stock, while the nitrogen compounds are usu-

ally present in oils derived from asphalt base crude oils, although they may be produced in the cracking of petroleum oil containing fixed nitrogen.

In the treatment of gasoline stocks or other hydrocarbons in liquid or vapor phase with water solutions of metallic salts, such, for example, as concentrated zinc chloride solution, at temperatures ranging from about 300 to 450° F. or lower, hydrolysis of the zinc chloride is effected to a limited extent, with the formation, usually, of small amounts of zinc oxychlorides and the liberation of hydrochloric acid, which reacts in part with the nitrogen base compounds, forming corresponding hydrochloric acid salt which is dissolved by the zinc chloride solution.

Now, I have discovered that if these used metallic salt solutions be treated with a metal base, a metal base or oxide suspended in water, a soluble metal base or oxide dissolved in water, and/or a metal base or oxide suspended in oil, such, for example, as the oxide or hydroxide of the metal in the metal salt solution, which may be zinc oxide or hydroxide, and/or the oxide or hydroxide of any of the metals heretofore enumerated, the nitrogen base impurities contained therein may be separated as an oily liquid by differential gravities thereof, and the solution revivified; also that the metal base is converted to the corresponding metal salt. The chemical reaction involved in this revivification operation when zinc oxide is used may be expressed as follows:

An object of the invention is to revivify metallic salt solutions which have been used to purify and refine hydrocarbon oil, so that the revivified metallic salt solution may be continuously used for the further purification and refining of hydrocarbon oils.

Another object of the invention is to revivify metallic salt solutions which have been used to purify and refine hydrocarbon oils, with an oxide or hydroxide of a metal, whereby the original active power of the salt solution may be substantially restored, and the oxide or hydroxide of the metal employed for the revivification converted into a metal salt which is also suitable for use in combination with the revivified solution to purify and refine hydrocarbon oil.

Another object of the invention is to recover nitrogen base hydrocarbons in commercially valuable form.

I have further discovered that the restoring of

the active power of the salt solutions, the recovery of the impurities in commercially valuable form, and the conversion of the oxide or hydroxide employed for the revivification into salt solutions suitable for purifying and refining hydrocarbon oil, may be most economically conducted in apparatus which will be herein described. Reference is therefore made to the accompanying drawing, which illustrates diagrammatically the preferred apparatus in which the process may be conducted.

In the drawing, 1 represents generally a pipe for conveying spent metallic salt solution, which has been used for purifying and refining hydrocarbon oils, from a source of supply to filter press 2. A container or tank 4 is stationed below filter press 2 to hold the metal sulphide separated from the spent metallic salt solution. Pipe 3 connects the outlet of filter press 2 to settling tank 5. Pipe 6, controlled by valve 7, connects settling tank 5 at the bottom to a tank 8 for holding separated oil. A pipe 10, controlled by valve 9, connects tank 8 to a storage not shown.

25 A branch pipe 12, controlled by valve 11, connects pipe 6 to the inlet of pump 13. Pipe 14 connects the discharge side of pump 13 to treating tank 15. A mechanically operated mixer 18 of any well known type is stationed within tank 15. 30 Pipe 16, controlled by valve 17, connects treating tank 15 at the top to a source of water supply. Pipe 21, controlled by valve 22, connects treating tank 15 at the top to a source of metallic oxide or hydroxide, and/or metallic oxide or hydroxide 35 dissolved or suspended in water or an oil.

Pipe 23, controlled by valve 24, connects treating tank 15 at the bottom to the inlet of pump 25. Pipe 26, controlled by valves 27 and 40, connects the discharge side of pump 25 to tank 37, 40 which is used to hold the nitrogen base oils separated in the process, and which may be intermittently transferred to other storage through pipe 38, controlled by valve 39. A branch pipe 28, controlled by valve 29, connects pipe 26 to a 45 heater or cooler 30. Pipe 31 connects heater or cooler 30 to treating tank 15 near the top. A branch pipe 32, controlled by valve 33, connects pipe 26 to revivified salt solution tank 34. From tank 34 the revivified salt solution may be transferred through pipe 35, controlled by valve 36, to 50 other storage or a treater and used thereafter for treating hydrocarbon oils of any type.

The preferred process as carried out in the apparatus just described is as follows:

55 A water solution of metallic salt or salts, such as a substantially concentrated solution of zinc chloride or other salts, which have been used for purifying hydrocarbon oils and contain impurities, such as metal sulphides, emulsified oil 60 and nitrogen base salts, as heretofore described, is caused to flow through pipe 1 under pressure, and then through filter press 2 wherein the flocculent solid impurities are separated from the liquid contents and the emulsified oil liberated. 65 The flocculent solid impurities, consisting principally of metal sulphides, which collect on the filter plates of filter press 2, may be intermittently removed and dropped into metal sulphide tank 4. These metal sulphides which are separated from the salt solution to be revivified may be conveyed from tank 4 to other apparatus and reconverted to the metallic salt solution for further use by methods known in the art, such, for example, as roasting in the presence of air and 70 thereafter treating the metal oxide formed with

water solutions of hydrochloric acid or other mineral acids.

The filtered salt solution, containing the liberated oil and nitrogen base salts, passes from filter press 2 through pipe 3, and then into settling tank 5 wherein the liberated oil collects, forming a top layer, and is separated from the salt solution containing the nitrogen base salts. The salt solution, containing the nitrogen base salts in solution, is conveyed from tank 5 through pipe 6, pipe 12 and into the inlet side of pump 13, with valve 11 open and valve 7 closed. Pump 13 discharges the salt solution containing the dissolved nitrogen base salts through pipe 14 and into treating tank 15. After discharging all 15 the salt solution or bottom layer from tank 5 into tank 15, the remainder comprising the liberated oil is transferred from tank 5 into separated oil tank 8 through pipe 6, with valve 7 open and valve 11 closed. The separated oil 20 which is collected in tank 8 may be conveyed to other storage through pipe 10, controlled by valve 9, and thereafter used for purposes known in the art.

The salt solution containing the nitrogen base 25 salts in solution, in treating tank 15, is commingled with the necessary amount of a metallic base, such as zinc oxide, which may be suspended in a fluid such as water, or an oil which is a solvent of the nitrogen bases. The metallic base, 30 suspended in water or in a solvent oil, may be introduced into treating tank 15 through pipe 21, controlled by valve 22, and/or the metallic base in a comminuted solid state may be introduced directly into treating tank 15 without the employment of a fluid suspension medium, in which case a mechanical conveyor may be used and water introduced into treating tank 15 through pipe 16, controlled by valve 17, to dilute the metallic salt solution to any required degree in 35 order to facilitate the separation of the liberated nitrogen bases and form a top layer above the salt solution. It is preferred that the quantity of water used to dilute the salt solution be regulated so that the gravity of the resultant salt 40 solution will be greater than the liberated nitrogen bases, in order that the nitrogen base oils 45 will form as a top layer.

After the required amount of metallic base and water have been introduced into treating 50 tank 15, containing the salt solution to be revivified, agitation and commingling of the metallic base with the salt solution is effected by operating mechanical stirrer 18. Also, preferably, the mixture of the metal base and salt solution is 55 heated to a temperature of about 150° F., more or less, in order to facilitate the chemical reaction between the base and the nitrogen base salts contained in the solution. This heating operation may be carried out by opening valves 24 and 29 and operating pump 25 with valve 27 closed, whereby the mixture is caused to circulate, passing from the bottom of tank 15 through pipe 23, pipe 26, pipe 28, heater 30, pipe 31, and then back into treating tank 15 near the top. After 60 the mixture of the metallic base and salt solution has been commingled and heated or cooled to the required degree, and a substantially complete liberation of the nitrogen bases has been effected, the operation of mechanical stirrer 18 65 and pump 25 is discontinued.

After standing and settling, the liberated nitrogen bases separate as an oily liquid from the treated salt solution, forming a top layer. The 70 revivified salt solution is separated from the ni- 75

5 trogen base oils and withdrawn from tank 15 into revivified salt solution tank 34, by operating pump 25 with valves 24, 27 and 33 open and valves 29 and 40 closed, after which the top layer 5 of nitrogen base oils is withdrawn into tank 37 by closing valve 33 and opening valve 40.

10 The revivified salt solution contained in tank 34 may be transferred to other storage through pipe 35, controlled by valve 36, and thereafter 15 employed for the further treatment of hydrocarbon oil, either with or without concentration, and/or with the further addition of salt solution thereto. The nitrogen base oils collected in tank 37 may be withdrawn to other storage 15 through pipe 38, controlled by valve 39, and thereafter used for purposes known in the art.

20 The quantity of metal base used to revivify metallic salt solutions which have been used to refine petroleum oils may vary through a wide 20 range, depending upon the per cent of nitrogen base salts contained in the solution. As a specific example, 1000 gallons of a concentrated water solution of zinc chloride containing 10 per cent of organic nitrogen bases, which had been used 25 to treat gasoline stock produced by cracking high boiling California petroleum oil stock, required 300 pounds of dry zinc oxide and 700 gallons of water to liberate and separate the nitrogen bases contained therein, and produce a usable or re- 30 vivified zinc chloride solution.

35 While the process herein described is well adapted for carrying out the objects of the present invention, various modifications and changes in the treatment may be made to suit any type 35 of contaminated salt solution without departing from the spirit of the invention, and the invention includes all such modifications and changes as appear within the scope of the appended claims.

40 I claim:

1. A process of revivifying used water solutions 45 of heavy metal salts, containing nitrogen bases and other organic extracted constituents resulting from the treatment of hydrocarbon oil with a water solution of metal salt at temperatures ranging from about 300 to 450° F., comprising, 50 commingling the used salt solution with a metallic base and then separating the liberated constituents from revivified salt solution.

55 2. A process of revivifying used water solutions of heavy metal salts, containing nitrogen bases and other organic extracted constituents resulting from the treatment of hydrocarbon oil with a water solution of metal salt at temperatures ranging from about 300 to 450° F., as in 55 claim 1, in which the metallic base is an oxide of a metal.

3. A process of revivifying used water solutions 60 of heavy metal salts, containing nitrogen bases and other organic extracted constituents resulting from the treatment of hydrocarbon oil with a water solution of metal salt at temperatures ranging from about 300 to 450° F., as in 65 claim 1, in which the metallic base is a hydroxide of a metal.

4. A process of revivifying used water solutions 70 of heavy metal salts, containing nitrogen bases and other organic extracted constituents resulting from the treatment of hydrocarbon oil with a water solution of metal salt at temperatures ranging from about 300 to 450° F., as in 75 claim 1, in which the metallic base is an oxide of the metal of the metal salt solution.

5. A process of revivifying used water solutions 75 of heavy metal salts, containing nitrogen bases

and other organic extracted constituents resulting from the treatment of hydrocarbon oil with a water solution of metal salt at temperatures ranging from about 300 to 450° F., as in claim 1, in which the metallic base is zinc oxide. 5

6. A process of revivifying used water solutions of heavy metal salts, containing nitrogen bases and other organic extracted constituents resulting from the treatment of hydrocarbon oil with a water solution of metal salt at temperatures ranging from about 300 to 450° F., as in claim 1, 10 in which the separated constituents are composed principally of nitrogen base compounds.

7. A process of revivifying used water solutions of heavy metal salts, containing nitrogen bases and other organic extracted constituents resulting from the treatment of hydrocarbon oil with a water solution of metal salt at temperatures ranging from about 300 to 450° F., comprising, 15 commingling the used salt solution with a metallic base suspended in water, thereby converting the metallic base into a metallic salt, and then separating the liberated constituents from revivified salt solution, containing the metallic salt formed from the metallic base dissolved therein. 20

8. A process of revivifying used water solutions of heavy metal salts, containing nitrogen bases and other organic extracted constituents resulting from the treatment of hydrocarbon oil with a water solution of metal salt at temperatures ranging from about 300 to 450° F., as in 30 claim 7, in which the commingled mixture of salt solution and metallic base is heated.

9. A process of revivifying used water solutions of heavy metal salts, containing nitrogen bases and other organic extracted constituents resulting from the treatment of hydrocarbon oil with a water solution of metal salt at temperatures ranging from about 300 to 450° F., comprising, 35 commingling the used salt solution with a metallic base dissolved in water, and then separating the liberated constituents from revivified salt solution. 40

10. A process of revivifying used water solutions of heavy metal salts, containing extracted constituents and nitrogen base acid salts resulting from the treatment of hydrocarbon oil with a water solution of metal salt at temperatures ranging from about 300 to 450° F., comprising, 45 commingling the used salt solution with a metallic base and water, heating the commingled mixture to an optimum temperature to cause a chemical reaction between the nitrogen base acid salt and the added metallic base, and then 50 separating the liberated nitrogen base constituents from revivified salt solution.

11. A process of revivifying used water solutions of heavy metal salts, containing extracted constituents and nitrogen base acid salts resulting from the treatment of hydrocarbon oil with a water solution of metal salt at temperatures ranging from about 300 to 450° F., as in claim 10, 55 in which the amount of water added along with the metallic base is regulated so as to produce 60 revivified salt solution having a greater density than the liberated organic base constituents.

12. A process of revivifying used water solutions of heavy metal salts, containing nitrogen bases and other organic extracted constituents resulting from the treatment of hydrocarbon oil with a water solution of metal salt at temperatures ranging from about 300 to 450° F., comprising, 70 commingling the used salt solution with a metallic base suspended in an oil which is a 75

solvent of the constituents to be separated, thereby converting the metallic base into a metallic salt, and then separating the liberated constituents, dissolved in the oil from revivified salt solution.

5 13. In the process of revivifying used water solutions of heavy metal salts, containing nitrogen bases and other organic extracted constituents resulting from the treatment of hydrocarbon oil with a water solution of metal salt at temperatures ranging from about 300 to 450° F., the step which comprises, neutralizing the extracted constituents with a base, and then sep-

arating the liberated constituents from the salt solution.

14. A process of revivifying used water solutions of heavy metal salts, containing metal sulphides, nitrogen bases and other extracted constituents resulting from the treatment of hydrocarbon oil with a water solution of metal salt at temperatures ranging from about 300 to 450° F., comprising, separating the metallic sulphides and commingling the resultant salt solution with a metallic base, and finally separating the liberated constituents from the salt solution.
